METALLIC INGOT MOLD AND INGOT

Emil Gathmann, Baltimore, Md.

Application July 20, 1934, Serial No. 736,268

9 Claims. (Cl. 22—139)

This invention relates to metallic ingot molds and ingots and more particularly molds and ingots of generally rectangular contour of the general character disclosed, for example, in my prior 5 United States Patents 1,745,089 of January 28, 1930, 1,892,569 of December 27, 1932 and 1,913,924 of June 13, 1933.

As is now well known to those familiar with the art, a steel ingot, irrespective of its physical 10 condition or chemical analysis, when stripped from the mold and placed in the soaking pit or reheating furnace, is merely a surface-chilled casting; and until work is done upon all its surfaces in the reduction of the coarse-grained crystals, the ingot inevitably has the weakness inherent 15 in castings as compared to forgings. The reduction of the section of the ingot should, therefore, be so accomplished that no unworked surface portion receives appreciable deformation in 20 reduction or working of adjacent portions.

In my Patent 1,745,089 referred to above, I have disclosed and claimed a mold and ingot contour in which the sides are provided with relatively narrow primary side portions which extend 25 relatively outward beyond the adjacent corners so that during the initial deformation in the rolls the corners are not unduly worked and the side portions adjacent to the primary side portions are not appreciably stressed. By virtue of this 30 contour, the ingot may be reheated without danger of corner burning and the ingot metal will be consolidated in the rolling mill operations without the setting up of local strains which would have a tendency to produce cracks and 35 tears.

When molten steel is poured into a metallic ingot mold, it solidifies through the formation of dendritic and free or equiaxial crystals, due to the absorption of heat by the surrounding mold walls. The ingot metal immediately adjacent the mold walls is cooled rapidly and crystallizes in 40 the form of dendrites, which grow into the mother liquid at right angles to the mold walls. As the dendrites progress in their growth and the 45 temperature of the liquid adjacent the dendritic structure is lowered, the formation of free or equiaxial crystals begins. The ratio of the depth in cross section of the ingot metal comprising 50 dendritic crystalline structure to the cross sectional width of the ingot as a whole depends upon such factors as the pouring temperature and the cross sectional area of the ingot, and, depending upon the latter factor, the depth of the area 55 of dendritic crystallization, with ordinary commercial pouring temperatures, is from one-sixth

to one-fifth of the cross section of the ingot considered as a whole.

The dendritic crystals grow in lines perpendicular to the mold walls defining the contour of the ingot, and, where the contour near the mid portions of the ingot sides is shaped by relatively small radii, resulting in relatively small curved convex surfaces on the ingot, the lines of dendritic crystallization extending inwardly from such surfaces will intersect within the zone of 10 dendritic crystallization. This often results in the formation at their focal points of what are known as cleavage planes, which are zones of weakness in the ingot structure.

In my Patent 1,892,569, I have disclosed and 15 claimed an ingot similar to that disclosed in my Patent 1,745,089, in that it comprises relatively narrow primary side portions adapted to be initially contacted by the rolls, the contour of the ingot of Patent 1,892,569 differing specifically 20 however from that disclosed in Patent 1,745,089 in that the radii of the arcs defining the outwardly curved side portions are of such length that the theoretical lines of growth of dendritic crystals from the primary sides inwardly converge 25 toward focal points lying within the zone of free, equiaxial crystals. Ingots having this contour have been found to be more free from cleavage planes, due to the intersection of the lines of growth of the dendrites, than ingots of corrugated side contour previously made.

The present invention has for an object the provision of a mold and ingot contour which still further avoids and practically eliminates the converging of the lines of growth of the dendrites towards foci, thus preventing the formation of cleavage planes. In the preferred form, my invention consists in the provision of a mold and/or ingot contour including primary side portions which extend outwardly beyond the adjacent corners and which are flanked by spaced flat or substantially flat salients, whereby the lines of growth of the dendrites from the side portions inwardly from each side wall portion 45 either diverge or are substantially parallel.

The more specific nature of the objects of the invention will become apparent from a reading of the following detailed description, the appended claims, and the accompanying drawings 50 in which:

Figure 1 is a vertical sectional view of an ingot mold having a matrix contour in accordance with my invention;

Figure 2 is a horizontal sectional view taken 55

on the line 2-2 of Figure 1, and drawn on an enlarged scale;

5 Figure 3 is an enlarged fragmentary horizontal sectional view of a mold having a contour in accordance with my invention;

Figure 4 is a perspective view of an ingot having a contour in accordance with the invention;

10 Figure 5 is a horizontal sectional view of the ingot shown in Figure 4; drawn on an enlarged scale; and

Figure 6 is a fragmentary horizontal sectional view of the ingot shown in Figures 4 and 5 and drawn on an enlarged scale.

15 For purpose of illustration, a mold M of the big-end-up Gathmann type, necked in at the bottom as at 1, is shown in Figures 1 and 2.

The preferred contour of the cross section of the mold matrix in accordance with the present invention is shown in Figures 2 and 3, from 20 which it will be noted that the horizontal cross section of the mold matrix is of generally rectangular contour and is defined by four primary sides 2, each side being connected to an adjacent side by outwardly arched primary corners 3 by 25 means of secondary corner portions 4 preferably of inwardly arched contour, and which converge inwardly from the primary sides 2, that is, the secondary corner portions are inclined inwardly from the primary sides 2 to the corner walls 3. 30 Salients 5, which are flat or substantially flat, flank and are connected to the primary sides 2, forming a part thereof. These salients 5 are interposed between and connect the primary sides 2 and the adjacent secondary corner portions 4 35 and are relatively narrow as compared with the width of the curved walls 2, preferably being about one-third the width of the latter. The salients 5 of each wall are disposed further from a plane a, passing through the center of the 40 mold and parallel to the wall taken as a whole, than the inwardly curved portions 2 and 4. That is, the salients 5 lie in planes P which are parallel to but spaced outwardly from planes 2 tangent to the corners 3.

45 An ingot I of the kind produced in a mold such as described with reference to Figures 1, 2 and 3 is shown in Figures 4, 5 and 6. The contour of the ingot, of course, will correspond substantially to the contour of the mold matrix. 50 Accordingly, the various portions of the ingot walls are designated by reference characters the same as those designating the corresponding wall portions of the mold, with the exception that the characters applied to the ingot are primed. 55 Thus the ingot is of generally rectangular contour and is defined by four primary sides 2', each side being connected to an adjacent side by outwardly arched primary corners 3' and a secondary corner portion 4' which preferably is 60 of inwardly arched contour. Flat, or substantially flat, salients 5' flank and form part of the primary sides 2', connecting them to the adjacent secondary corners 4'.

65 The relative extents of the zones of dendritic and free or equiaxed crystals forming the ingot structure are shown graphically as merging one with the other by means of dotted lines X in Figure 6 of the drawings. For the reasons explained in my Patent 1,745,089, of January 28, 70 1930, it is desirable that the primary sides 2' be given an inwardly curved contour and that these sides be relatively narrow as compared to the cross section of the ingot. As explained in my Patent 1,913,924, the length of the radii 6 of the corners 75 3 of the mold should be between one-eighth and

one-eighteenth, and preferably about one-tenth, of the length of the cross section b of the mold. This will produce an ingot having corners 3' the length of the radii 6' of which will be between one-tenth and one-twentieth, and preferably about one-twelfth, the dimensions b'; and, as explained in my Patent 1,892,569, these relative dimensions are such that the ingot corners are possessed of the desired rolling properties, and at the same time the formation of cleavage planes 10 due to the intersection of lines of growth of dendrites from the corners 3' inwardly is avoided.

15 In accordance with the present invention the advantages of the corrugated side contour including outwardly extended primary sides are retained and the crystalline structure still further improved by the provision of the flat or substantially flat salients 5 in the mold, (3' in the ingot). The lines of growth Y of the dendritic crystals 20 from the various surface portions of the ingot inwardly are shown in Figure 6. It is apparent that these lines are substantially perpendicular to the ingot surface from which they grow and, since the surface portions 2' and 4' are inwardly 25 curved, the lines of growth inwardly from each of these portions will diverge, whereas, the salients 5' being flat, the lines of growth inwardly therefrom will be substantially parallel and the improved physical structure of ingots having a 30 contour in accordance with my present invention is due principally to the employment of these flat or substantially flat salients. The new contour is such that none of the lines of growth of dendrites from the sides of the ingot converge 35 towards foci, whereby the danger of forming cleavage planes or segregation, previously due to converging of the lines of dendritic growth toward foci, is eliminated. Moreover, none of the advantages of a corrugated mold are lost by the 40 use of the flat or substantially flat salients or primary side portions 5' because the inwardly curved surfaces remain in the same relative arrangement as heretofore has proved so successful in preventing the formation of surface cracks in 45 the ingot or the finished bloom or billet.

50 In the form shown, each side of the mold includes two spaced salients or primary wall portions 5 which are relatively narrow as compared to the side wall considered as a whole, i. e., the entire extent of the side wall from one corner wall 3 to the next, but it will be understood that the invention is not restricted to contours including only two such primary salients or primary 55 side portions.

I claim:

1. An ingot mold having a matrix wall comprising a plurality of alternately arranged and connected flat portions and inwardly curved portions, the flat portions being relatively narrow as 60 compared to the curved portions and being disposed further from a plane passing through the center of the mold and generally parallel to said matrix wall taken as a whole than the inwardly curved portions. 65

2. An ingot mold having a matrix wall including a plurality of spaced substantially flat primary wall portions; and a plurality of inwardly curved wall portions connected to said primary wall portions, said primary wall portions constituting a 70 smaller part of the whole wall surface than the curved portions.

3. An ingot mold having matrix corner walls and matrix side walls, one matrix side wall including a plurality of substantially flat primary 75

- wall portions; an inwardly curved wall portion intervening between and connecting said primary wall portions; and other wall portions connected to said primary wall portions and extending to 5 the adjacent matrix corner walls, said other wall portions being inclined inwardly from the primary portions to the corner walls.
4. An ingot mold of generally rectangular contour including side walls joined by outwardly curved corner walls, two opposite side walls including substantially flat primary wall portions spaced from each other and each spaced from the nearest outwardly curved corner wall, inwardly curved wall portions intervening between and 10 connecting the primary wall portions on each of said two sides, and other wall portions intervening between the outwardly curved corner walls and the adjacent primary wall portions.
5. An ingot mold of generally rectangular contour including side walls joined by outwardly curved corner walls, two opposite side walls including substantially flat primary wall portions spaced from each other and from the adjacent outwardly curved corner walls, inwardly curved 15 wall portions intervening between and connecting the primary wall portions on each of said two sides, and other wall portions intervening between the outwardly curved corner walls and the adjacent primary wall portions, the primary wall portions of said two sides lying in planes respectively parallel to but spaced outwardly from planes tangent to the outwardly curved corner walls at the ends of the respective sides.
6. An ingot mold of generally rectangular contour including four side walls and four outwardly curved corner walls connecting the side walls, each side wall including at least two spaced substantially flat primary wall portions, an inwardly curved wall portion intervening between and connecting adjacent primary side wall portions, and other inwardly curved wall portions intervening between and connecting corner walls with adjacent primary side wall portions.
7. A metallic ingot having convex corners and intervening sides of corrugated contour including three inwardly curved side portions and two substantially flat side portions, the lines of growth of dendritic crystals inwardly from said corners converging, the lines of growth of dendritic crystals inwardly from the inwardly curved side portions diverging, and the lines of growth inwardly from the substantially flat side portions being substantially parallel.
8. A metallic ingot of generally rectangular cross-sectional contour, a side surface of which comprises a plurality of alternately arranged and connected flat portions and inwardly curved portions, the flat portions being relatively narrow as compared to the curved portions and being disposed further from a plane passing through the center of the ingot and generally parallel to said surface taken as a whole than the inwardly curved portions.
9. An ingot mold having a generally rectangular cross sectional contour including four side walls and four corner portions intervening between and connecting the side walls, two oppositely disposed side walls each including at least two relatively narrow substantially flat primary wall portions and inwardly curved wall portions intervening between and connecting the said primary side wall portions, and other wall portions intervening between and connecting the adjacent primary side wall portions with the corner portions, said other wall portions extending inwardly from the plane of the primary wall portions towards the corner portions.

EMIL GATHMANN.
